TORPEDO

George Wise, Brooklyn, N. Y.

Application January 4, 1943, Serial No. 471,253

5 Claims. (Cl. 114—20)

(Granted under the act of March 3, 1883, as
amended April 30, 1928; 370 O. G. 757)

The invention described herein may be manufactured and used by or for the Government of the United States for governmental purposes without the payment to me of any royalty thereon in accordance with the provisions of the act of April 30, 1928 (Ch. 460, 45 Stat. L. 467.)

This invention relates to torpedoes, but more particularly to a multiple torpedo so constructed and arranged that two auxiliary torpedoes may be connected to and launched with a central carrying torpedo so that, by suitable time controlled releasing mechanism, the two auxiliary torpedoes will be detached from the central carrying torpedo and be self-propelled on their run to the target independently of the central carrying torpedo.

The invention has for its object to increase the striking power of torpedoes and consequently their damaging effect, as the multiple torpedo may be arranged to strike the target at three different points.

A further object of the invention is to arrange the multiple torpedo so that it may be carried by and launched from the conventional torpedo tube on the decks of torpedo carrying surface vessels, whereby no change, alteration nor modification of the conventional torpedo tubes of such vessels will be required.

A further object of the invention is to adapt my multiple torpedo to be launched from airplanes in the conventional manner.

With these objects in view, the invention consists of the combinations and arrangements for connecting the torpedo assembly into a single unit for launching, and the invention also consists of the construction of the auxiliary torpedoes, all of which will be first fully described and afterwards specifically pointed out in the appended claims.

Referring to the accompanying drawings:

Fig. 1 is a side elevation of the multiple torpedo constructed in accordance with my invention;

Fig. 2 is a bottom plan view of the same;

Fig. 3 is a front elevation of the same;

Fig. 4 is a longitudinal sectional view through one of the auxiliary torpedoes and a fragmentary view of the time controlled releasing mechanism in the central carrying torpedo;

Fig. 5 is a fragmentary view of the said time controlled releasing mechanism illustrating the same in position for releasing the two auxiliary torpedoes;

Fig. 6 is a perspective view of one of the vertical directional rudders and its actuating linkages;

Fig. 7 is a side elevation of the multiple tor-

pedo illustrating the embodiment particularly adapted to be launched from airplanes;

Fig. 8 is a front elevation of the same;

Fig. 9 is an exploded view of the multiple torpedo assembly illustrating the positions that the component parts assume upon the release of the auxiliary torpedoes from the central carrying torpedo;

Fig. 10 is a diagrammatic view illustrating the multiple torpedo assembly showing the positions that the component parts assume upon the release of the auxiliary torpedoes from the central carrying torpedo;

Fig. 11 is a vertical longitudinal section through one of the auxiliary torpedoes;

Fig. 12 is a view partly in section and partly in elevation illustrating the time controlled releasing mechanism employed in the embodiment shown in Figs. 7 to 11; and

Fig. 13 is a fragmentary sectional view showing one of the releasing detents of Fig. 12 in releasing position.

Like numerals of reference indicate the same parts throughout the several figures in which:

1 indicates the central carrying torpedo which is in all respects of the conventional type except that it contains therein near the nose thereof a time controlled releasing mechanism 2, as shown in Figs. 4 and 5, for releasing the two auxiliary torpedoes 6 as will be hereinafter described.

30 The central torpedo 1 has the usual shell or casing 3, to which is attached near its forward end the two extending arms 4 of the two auxiliary torpedo tubes 5. Each of these tubes 5 is open at its forward end as indicated at 7, and have closed rear ends 8, as shown in Fig. 4. The auxiliary torpedoes 6 are inserted in their tubes 5 through the open forward ends 7 as will be apparent from the drawings.

Each auxiliary torpedo has the usual war head of conventional high explosive 9 and also the conventional firing pin 10 in its nose, by means of which the war head is ignited by impact as is usual in conventional torpedoes.

Longitudinally extending through the body of each auxiliary torpedo 6 is a tubular container 11 for the propulsive rocket powder 11', which tubular container 11 is closed by a plate 12 at its rear end. Extending from the forward end of the rocket powder container 11 and positioned alongside the same, is a fuse 13 which enters the container 11 and the rocket powder 11' therein at the rear end of the same.

Fixed to the forward end of the fuse 13 is an igniter 14 of match head material, while a lever 15 pivoted at 17 carries on its after end a match

igniting abrasive material 16 arranged in relation to the igniter 14 so that the match igniting abrasive material 16 will wipe the match head igniter and ignite the match head material when the forward end of the said pivoted lever 15 is depressed, as will be clearly seen from an inspection of Fig. 4. Formed in each of the arms 4 on the shell 3 of the central torpedo 1, is a bore 18 into which the L-shaped forward end of the lever 15 slightly extends. Also positioned in this bore 18 is a plunger 19 in contact with the said L-shaped end of the lever 15.

Within each of the auxiliary torpedoes 6 is a compartment 20 for the control apparatus for steering the auxiliary torpedoes. This control apparatus is of the usual conventional type employed in torpedoes and I lay no claim to originality thereto. Therefore I have not illustrated the same in the drawings nor described it herein since the construction and operation of the conventional torpedo control apparatus is well known and understood by those skilled in the art.

Extending rearwardly from the control apparatus compartment 20 are two links 21 and 28, by means of which the movements of the control apparatus are communicated to the vertical steering rudders 26' and to the horizontal rudders 31, the latter being shown in Fig. 7.

The said link 21 is connected to a lug 22 on a collar 23 (Fig. 6) slidably mounted on the tubular container 11, while links 24 pivoted on the collar 23 are connected to a crank 25 fixed to each rudder post 26 of the vertical directional rudders 26'.

The link 28 extending from the control apparatus connects with a lug 29 on a similar collar 30 also slidably mounted on the tubular container 11 and by suitable linkages shown in dotted lines and which are the counterparts of the links 24 just described but slightly longer, connect with cranks fixed on the rudder posts of the two horizontal rudders 31 precisely the same as has just been described.

Referring now to the time controlled releasing mechanism 2 in the central carrying torpedo 1 (Fig. 4), it will be seen that this mechanism includes an annular member 32 fixed on a threaded shaft 33 which is longitudinally movable but not rotatable in the housing 34 of the clock timing mechanism 36. Mounted on the said threaded shaft 33 is a nut 35 having a toothed periphery in mesh with the clock-work mechanism 36. This toothed nut 35 is rotatable on the threaded shaft 33, but is restrained from longitudinal movement, so that upon rotation of the nut by the clock-work mechanism the threaded shaft 33 is caused to move longitudinally with respect to the clock-work casing 34.

On the underside of the casing 3 of the central torpedo 1 and in convenient position for manual operation is the time setting dial 37 for the clock-work mechanism 36. Any conventional timing mechanism may be employed and as such timing mechanisms are common in many arts and their construction and operation are generally well known and understood, the specific construction of the same is not of my invention.

Referring to the annular member 32 of the releasing mechanism, it will be seen from Fig. 4 that this annular member 32 has an annular flange or projection 40 for engagement with the L-shaped end 39 of the plunger 19, and it will be seen that this plunger 19 passes through a bracket 38 and has fixed thereon a collar 42 between which collar and the underside of the

bracket 38, is a coil spring 41 of extension strain, so that when the plunger 19 is in engagement with the annular member 32 of the releasing member, the coil spring 41 is in a state of compression.

Having thus described the embodiment illustrated in Figs. 1 to 5 which is adaptable to be launched from the conventional torpedo tube on the deck of surface vessels, its operation is as follows:

The conventional torpedo tubes carried on the decks of surface vessels have their forward open ends cut away downwardly and rearwardly as shown in dotted lines in Fig. 1. This cut-away portion permits the use of my multiple torpedoes in such conventional torpedo tubes without the necessity of change or modification in said tubes, since the projecting arms 4 by which the two auxiliary torpedoes are connected to the shell of the central carrying torpedo lie in the cut-away portion of the torpedo tube as shown in Fig. 1.

The two auxiliary torpedoes 6 may have their longitudinal axes parallel with the longitudinal axis of the central carrying torpedo 1, or they may preferably have their longitudinal axes divergent from the longitudinal axis of the central carrying torpedo 1, as shown in Figs. 2 and 3, so that upon release of the auxiliary torpedoes 6, as will be presently described, the courses of the two auxiliary torpedoes 6 will diverge from the course of the central carrying torpedo 1 on their runs to the target as indicated by the dotted lines in Fig. 10.

The time controlled release mechanism 2 having been set by the dial 37 (Fig. 4), and the multiple torpedo having been launched from its torpedo tube, it starts its run to the target as indicated by the dotted line in Fig. 10. After the desired interval of time has elapsed, as for instance at the position shown in Fig. 10, the two auxiliary torpedoes 6 are released from the central carrying torpedo 1, as will now be described.

Referring to Figs. 4 and 5, the clock-work mechanism 36 rotates the toothed nut 35 on the threaded shaft 33 which causes the annular plunger-engaging member 32 to be moved toward the clock-work casing 34 until the annular plunger engaging flange 40 is moved entirely out of physical contact with the L-shaped ends 39 of the plungers 19 and into the released position shown in Fig. 5. The two plungers 19 thus being released are each moved by its coil spring 41 so as to act upon the L-shaped end of the lever 15 causing this lever to rock on its pivot 17 and wipe the match igniting abrasive material 16 over the match-head igniter 14 on the fuse 13 and ignite the same. The fuse 13 being thus ignited, the column of rocket powder 11' is caused to ignite at its rear end. This displaces the powder retaining plate 12 and permits the now burning rocket powder to react against the closed rear end 8 of the torpedo tube 5 which ejects the torpedo from its tube at high speed. When the torpedo is clear of its tube, the burning rocket powder reacts against the water and is thus propelled on its run to the target at high speed.

In the embodiment illustrated in Figs. 7 to 13 which is particularly adapted to be launched from torpedo airplanes, the two auxiliary torpedoes 6 are each provided with a concave side 53 so as to snugly conform to the cylindrical contour of the central carrying torpedo 1, when the three torpedoes are in assembled position shown in Fig. 8.

To retain the three torpedoes as a unit while

being launched from an airplane and for the initial part of their run to the target, a flexible band 50 having hooked members 51 adjustably secured to the band 50 by adjusting screws 52, encompasses the three torpedoes as shown in Figs. 7 and 8. These hooked end members 51 enter openings 58 in the sides 57 of the casing 54 for the time-controlled releasing mechanism 55, as shown in Fig. 12. The casing for this mechanism has a concave top to conform to the cylindrical contour of the central carrying torpedo 1, and is positioned under the central carrying torpedo 1 as shown in Figs. 7 and 8.

Within this casing is the time controlled releasing mechanism 55, which is set by a dial 56 on the rear end of the casing (Figs. 7 and 12). Pivoted at 59 and 60 are two detents 61 and 62 each having an upturned hooked end 63 for releasable engagement with the two hooked members 51 of the encompassing band 50. The inner ends of these pivoted detents 61 and 62 have short depending arms 64, while normally positioned between the two short depending arms 64 is the bar of a T-shaped member 65, by means of which the two pivoted detents 61 and 62 are maintained in normal horizontal position and in engagement with the two hooked members 51. The stem 66 of this T-member 65 is provided with a toothed rack shown in dotted lines in Fig. 12 which meshes with a pinion of the clock-work mechanism of the time-controlled releasing mechanism also shown in dotted lines in Fig. 12.

The internal construction of the two auxiliary torpedoes 6 of the embodiment illustrated in Figs. 7 to 13 is substantially the same as that of the embodiment shown in Fig. 4. However, in the embodiment shown in Fig. 11, there is only one sleeve 23 slidable on the cylindrical container for the rocket powder 11' to which sleeve 23 the link 21 connects for communicating movement of the central apparatus to the horizontal rudder 31 (Fig. 7) while the link 28 from the central apparatus passes directly to the vertical rudder 26'. Also in Fig. 11, the match igniting abrasive 16 is positioned on a pin 67 which pin is held in depressed position against the influence of a coil spring 71 by the encompassing band 50.

Having thus described the embodiment illustrated in Figs. 7 to 13, its operation is as follows:

The multiple torpedo having been launched from an airplane in the conventional manner, and the dial of the time controlled releasing mechanism having been set for the release of the two auxiliary torpedoes from the central carrying torpedo after the elapse of a certain period of time, the assembled torpedoes as shown in Figs. 7 and 8, start their run toward the target. The clock-work mechanism acting on the toothed rack of the central T-shaped element 65 gradually lowers this T-shaped element until it passes out of physical contact with the short depending arms 64 of the two pivoted releasing detents 61 and 62. Under the influence of the springs 70 acting on each of these detents, the hooked ends 63 thereof are moved down into position shown in Fig. 13 and out of engagement with the hooked members 51 of the encompassing band 50 which releases said band. By reason of its resiliency this band assumes the position shown in Fig. 9. The two auxiliary torpedoes are therefore released from the central carrying torpedo 1 and the time-controlled releasing mechanism falls away from the central carrying torpedo in the manner as shown in Fig. 9. At the same time,

the pin 50 (Fig. 11) which has been held in depressed position, by the encompassing band 50 and against the influence of its spring 71, is raised by this spring and the match igniting abrasive 16 thereon is wiped over the match head igniter 14 on the end of the fuse 13 and ignites the same. By means of the fuse 13, the rear end of the column of rocket powder 11' is ignited; the plate at the rear thereof is displaced and the burning rocket powder reacts against the water to propel the torpedo at high speed on its run to the target.

Having thus described the construction and operation of the two embodiments of my invention, I do not wish to limit myself to the exact constructions illustrated in the drawings and described herein, as various changes and modifications may be made therein which would fall within the limit and scope of this invention, and I consider myself clearly entitled to all such changes and modifications as come within the limit and scope of the appended claims.

I claim:

1. In a multiple torpedo, the combination with a torpedo of conventional design and construction forming a central carrying torpedo, of a pair of auxiliary torpedo tubes attached to the outside of the central carrying torpedo, the said auxiliary torpedo tubes having their longitudinal axes divergent from the longitudinal axis of the central carrying torpedo in a horizontal plane, an auxiliary torpedo in each of the auxiliary tubes, the position of attachment of the auxiliary torpedo tubes to the central carrying torpedo being close to the nose of the central carrying torpedo so as to adapt the assembly to conventional torpedo tubes for launching therefrom as a unit, each auxiliary torpedo including a war head and firing pin for detonating the war head upon impact of the torpedo, and including self-contained means for its propulsion independent of the central carrying torpedo, said propulsion means for the auxiliary torpedoes being normally inactive within the auxiliary torpedo tubes, and means for putting the self-contained propelling means of the auxiliary torpedoes in operation for simultaneously launching them from the auxiliary torpedo tubes and releasing them from the central carrying torpedo so that they each may be self propelled on divergent paths to a target.

2. In a multiple torpedo, the combination with a torpedo of conventional design and construction forming a central carrying torpedo, of a plurality of auxiliary torpedo tubes fixed to the outside of the central carrying torpedo, an auxiliary torpedo in each of the auxiliary tubes, the position of attachment of the auxiliary torpedo tubes to the central carrying torpedo being close to the nose of the central carrying torpedo so as to adapt the assembly to conventional torpedo tubes for launching therefrom as a unit, each auxiliary torpedo including a war head and firing pin for detonating the war head upon impact of the torpedo, and including self-contained means for its propulsion independent of the central carrying torpedo, said propulsion means for the auxiliary torpedoes being normally inactive within the auxiliary torpedo tubes and means for putting the self-contained propelling means of each of the auxiliary torpedoes in operation for launching them from the auxiliary torpedo tubes and releasing them from the central carrying torpedo so that each of them may be self propelled to a target.

3. In a multiple torpedo, the combination with

a torpedo of conventional design and construction forming a central carrying torpedo, of a pair of auxiliary torpedoes, each having its exterior longitudinally concaved to closely conform to the exterior contour of the central carrying torpedo for close physical contact therewith and to maintain the longitudinal axes of the auxiliary torpedoes parallel with each other and parallel with the longitudinal axis of the central carrying torpedo, a band encompassing the central carrying torpedo and the auxiliary torpedoes to connect them together for launching as a unit, each auxiliary torpedo including a war head and means for detonating the same upon impact of the torpedo, and including self-contained means for its propulsion independent of the central carrying torpedo, said propulsion means for the auxiliary torpedoes being inactive as long as the assembled torpedoes are connected together as a unit, and means for releasing the said encompassing band for disconnecting the auxiliary torpedoes from the central carrying torpedo and for putting the self-contained propelling means of each auxiliary torpedo in operation to propel the auxiliary torpedoes to the target independently of the central carrying torpedo.

4. In a multiple torpedo, the combination with a torpedo of conventional design and construction forming a central carrying torpedo, of a plurality of auxiliary torpedoes, a band encompassing the central carrying torpedo and the auxiliary torpedoes to connect them together for launching as a unit, each auxiliary torpedo including a war head and means for detonating the

same upon impact of the torpedo and including self-contained means for its propulsion independent of the central carrying torpedo, said propulsion means for the auxiliary torpedoes being inactive as long as the assembled torpedoes are connected together as a unit, and means for releasing the said encompassing band for disconnecting the auxiliary torpedoes from the central carrying torpedo and for putting the self-contained propelling means of each auxiliary torpedo in operation to propel the auxiliary torpedoes to a target independently of the central carrying torpedo.

5. In a multiple torpedo, the combination with a torpedo of conventional design and construction forming a central carrying torpedo, of a plurality of auxiliary torpedoes, means for connecting the central carrying torpedo and the auxiliary torpedoes together for launching as a unit, each auxiliary torpedo including a war head and means for detonating the same upon impact of the torpedo, and including self-contained means for its propulsion independent of the central carrying torpedo, said propulsion means for the auxiliary torpedoes being inactive as long as the assembled torpedoes are connected together as a unit, and means for effecting disconnection of the auxiliary torpedoes from the central carrying torpedo and for putting the self-contained propelling means of each auxiliary torpedo in operation to propel the auxiliary torpedoes to a target independently of the central carrying torpedo.

GEORGE WISE.
